UNITED STATES PATENT OFFICE.

SPENCER OTIS, OF CHICAGO, ILLINOIS, ASSIGNOR TO NATIONAL COAL DUMP CAR COMPANY, OF SOUTH DAKOTA, OF RAPID CITY, SOUTH DAKOTA, AND CHICAGO, ILLINOIS, A CORPORATION OF SOUTH DAKOTA.

BOTTOM-DUMPING CAR.

SPECIFICATION forming part of Letters Patent No. 739,914, dated September 29, 1903.

Application filed February 9, 1903, Serial No. 142,484. (No model.)

To all whom it may concern:

Be it known that I, SPENCER OTIS, a citizen of the United States, residing at Chicago, in the county of Cook and State of Illinois, have 5 invented certain new and useful Improvements in Bottom-Dumping Cars, of which the following is a specification.

This invention, as above stated, relates to that class of cars known as "bottom-dumping" cars—that is, cars provided with a substantially flat floor portion formed of a plurality of dumping-doors arranged at each side of the longitudinal center of the car—and particularly to the means by which such dumping-sections, which I will hereinafter term "dumping-doors," are raised and lowered and held in closed position, all of which will more fully hereinafter appear.

The principal object of the invention is to 20 provide a bottom-dumping car with self-adjustable chain mechanism by which the dumping-doors may be raised and lowered.

Further objects of the invention are to provide simple, economical, and efficient mechanism by which one or more of the dumping-doors may be held in closed position while the rest of the doors are free to operate, all of which will more fully hereinafter appear.

The invention consists principally in a bottom-dumping car having a door or doors arranged at either or both sides of the longitudinal center with their free ends at or near the outside of the car, rock-shaft mechanism, and chain or similar mechanism secured to 35 the rock-shaft and passed around and under the free edge of the door, whereby such chain mechanism is self-adjustable, substantially as hereinafter set forth.

The invention consists, further and finally, 40 in the features, combinations, and details of construction hereinafter described and claimed.

In the accompanying drawings, Figure 1 is a transverse sectional elevation of a portion 45 of a car constructed in accordance with these improvements. Fig. 2 is an enlarged sectional detail taken on the line 2 of Fig. 1 looking in the direction of the arrow. Fig. 3 is a sectional detail taken on the line 3 of 50 Fig. 2 looking in the direction of the arrow;

and Fig. 4 is an enlarged sectional view showing the independent door-locking mechanism, hereinafter more fully described.

In illustrating and describing these improvements I have only illustrated and will 55 describe that which I consider to be new, taken in connection with so much as is old, as will properly disclose the invention to others and enable those skilled in the art to practice the same, leaving out of consideration other and well-known mechanism which, if set forth herein, would tend only to confusion, prolixity, and ambiguity.

In the art to which this invention relates it is well known that where rock-shaft and 65 chain or similar mechanisms are used for the purpose of opening and closing the swinging doors of a bottom-dumping car such chain mechanisms are secured independently to each lateral edge of the door and to the rock-shaft. It is further well known that such chain mechanisms, owing to the inequality of the strains placed thereon, are apt soon or late to become unequally expanded, so that when the door is being opened or closed 70 more or less of the strain is apt to come on one chain than on the other, all of which tends to the manifest injury of the chain mechanism as well as other parts. This invention therefore is intended primarily to provide a 80 self-adjusting mechanism, such as a single chain passed around the free end of the door, so that any inequalities in the expansion or contraction of the chain will affect the entire chain and not a portion thereof, all of which 85 will be more fully hereinafter set forth.

In constructing the bottom-dumping car in accordance with these improvements I provide a supporting-frame portion having a plurality of center sills *a* and transverse deck-beams *b*. This supporting-frame portion is also provided with upwardly-extending side boards *c* and end boards *d*, which inclose the floor of the bottom portion of the car, so that it may be used as a dumping-bottom car or a 95 gondola car, as occasion requires or necessity demands.

In order to provide the bottom-dumping portion of the car, I make a plurality of swinging door-sections *e* and pivotally secure 100

them to the framework of the car at and along each side of the longitudinal center thereof, so that their free ends extend toward the outside of the car and when open swing downwardly and inwardly, so that the load, as can be seen from examination of Fig. 1, may be discharged to one or both sides of the railway-track.

In order to provide for a self-adjusting chain mechanism by which the swinging sections may be opened and closed and other mechanisms to be used in connection therewith, one or more rock-shafts *f* are provided and arranged longitudinally along each side 15 of the car and inside of the side boards, covered and protected by suitable housing *g*. Attached to each of these rock-shafts is a lifting chain or chains *h*, which has a link or links *i* inserted in each side thereof, formed 20 of a flattened bar of iron or steel passing through a similar-shaped perforation in the dumping-door, so as to prevent rotation, but permit of sliding movement. The lower part of the chain, as at *j*, is passed around 25 underneath the free edge of the door and in a groove *k*, formed in a convex bracket *l*, which is secured to the under side of the door, particularly as shown in Figs. 2 and 3.

From the foregoing description of construction and operation it will be seen that no matter how each side of the chain is contracted or expanded such contraction, expansion, or inequalities are compensated for by a movement of the chain in the bracket portion, so 35 that as the rock-shaft is rotated in either direction the chain mechanism is wound or unwound with the same strain on every portion or link thereof, all of which will be understood and appreciated by those skilled in the art.

40 It is well known that when bottom-dumping cars are used for the purpose of discharging coal or ore to each side of the track in a great many instances discharged material is dumped directly into wagons for the purpose of 45 transporting the same. It is also well known that in nearly every instance these dumping-cars are so constructed and arranged that all of the dumping-doors on each side of the car must be dumped at one and the same operation. It would seem, therefore, that it is 50 highly desirable to provide some mechanism by which one or more of these doors may be kept and held in closed position while the other doors are free to be operated as seems 55 desirable or necessary. In order to accomplish this result, I provide each side board of the car with a plurality of perforations *m*, in which is arranged a hooked depending bolt *n*, the lower end of which is provided with a 60 swinging button or latch *p*. When the parts are in their closed position, as shown in Figs. 1 and 4, this swinging button is arranged underneath the free edge of the dumping-door and in contact with a locking-plate *q*. When 65 it is desirable to open but one door, the door that it is desired to open, the operator hits the outer free end of the button *p* therefor

with a hammer, wrench, or similar article, so as to swing it around and away from contact with the free edge of the dumping-door. By 70 leaving the rest of the doors in their locked position the operator may rotate the rocking shaft, thereby permitting such single door to be opened and the material opposite the same dumped into a car or bin, as occasion may require, all of which will be understood and appreciated by those skilled in the art.

75 I claim—

1. In a car of the class described, the combination of a supporting-framework, a bottom portion formed of one or more dumping-doors pivoted at their inner edge and with their free or discharging ends extending outside to a point at or near the outer side of the car, rock-shaft mechanism, and chain mechanism 85 secured to the rock-shaft and passed around and under the free discharging end of the dumping-door section, substantially as described.

2. In a car of the class described, the combination of a supporting-framework, a bottom-dumping portion formed of a plurality of dumping-doors arranged longitudinally of the car with their free edges at or near the outer side of the car, rock-shaft mechanism, a single chain for each door the ends of which are secured to the rock-shaft and adapted to be wound around the same and passed downwardly through and underneath the lower portion of the free end of the discharging-door, substantially as described.

3. In a car of the class described, the combination of a supporting-frame portion, a bottom-dumping portion formed of a plurality of swinging door-sections pivotally secured to 105 the supporting-framework of the car at their inner edges and to each side of the longitudinal center of the same with their free edges extending out to a point at or near the outside of the car, a grooved bracket secured to 110 the lower portion of the free end of each dumping-door section, rock-shaft mechanism, and a single chain for each dumping-door section the free ends of which are secured to the rock-shaft and passed down, around and 115 through the grooved bracket on the lower side of the dumping-door, substantially as described.

4. In a car of the class described, the combination of a supporting-framework, a bottom-dumping portion formed of a plurality of swinging doors pivotally secured at their inner edges to the framework of the car and at each side of the longitudinal center of the same, a grooved bracket secured to the lower 120 surface of each of said dumping-doors and at or near its free edge, rock-shaft mechanism, a single chain for each dumping-door section the free ends of which are secured to the rock-shaft and adapted to be wound and unwound 125 around the same and passed down, around and through the grooved bracket on each dumping-door, and flattened links in such chains slidingly mounted in elongated perforations 130

in each dumping-door to permit a sliding movement of the chain therethrough but prevent a turning movement thereof, substantially as described.

5. In a car of the class described, the combination of a supporting-framework, a bottom-dumping portion formed of a plurality of swinging door-sections laid in a flat plane and pivoted at their inner edges to the framework of the car with their free outer edges extending to a point at or near the outer side of the car, and latch mechanism for each section to hold and lock such sections in their closed position and permit one or more of such doors 15 to be operated as desired, substantially as described.

6. In a car of the class described, the combination of a supporting-framework, a bottom-dumping portion formed of a plurality of 20 swinging doors laid in a flat plane longitudinally of the car pivoted at their inner edges to the supporting-framework and with their free outer edges extending to a point or points at or near the outer side of the car, 25 latch mechanism for each and every swinging door-section formed of a plurality of depending bolts having a swinging button on the lower end thereof arranged to contact and hold such swinging door-sections in their 30 closed position, substantially as described.

7. In a car of the class described, the combination of a supporting-framework, a bottom dumping portion formed of a plurality of swinging doors laid in a flat plane and ar-

ranged at each side of the longitudinal center of the car pivoted at their inner edges and with their free ends extending out to a point or points near the outer side of the car, and latch mechanism formed of a plurality of depending removable bolts having swinging 40 buttons at their lower ends adapted to contact and engage with the lower surface of the swinging doors and hold the same in their locked position while permitting one or more such doors to be operated as desired, substantially as described. 45

8. In a car of the class described, the combination of a supporting-framework, a bottom-dumping portion formed of a plurality of swinging doors laid in a flat plane and ar- 50 ranged at each side of the longitudinal center of the car pivoted at their inner edges and with their free ends extending out to a point or points near the outer side of the car, and latch mechanism formed of a plurality of depending removable bolts having swinging 55 buttons at their lower ends adapted to contact and engage with the lower surface of the swinging doors and hold the same in their locked position while permitting one or more 60 such doors to be operated as desired, with rock-shaft and chain mechanism for opening and closing such doors, substantially as described.
